US00D966880S

(12) **United States Design Patent** (10) **Patent No.:** **US D966,880 S**
(45) **Date of Patent:** **** Oct. 18, 2022**

(54) **FASTENER**

(71) Applicant: **Hill-Rom Services, Inc.**, Batesville, IN (US)

(72) Inventor: **Christine Michelle Lamb**, Sandy Hook, VA (US)

(73) Assignee: **HILL-ROM SERVICES, INC.**, Batesville, IN (US)

(**) Term: **15 Years**

(21) Appl. No.: **29/755,961**

(22) Filed: **Oct. 23, 2020**

(51) LOC (13) Cl. **08-08**

(52) U.S. Cl.

USPC **D8/395**; D24/184

(58) **Field of Classification Search**

(57) **CLAIM**

The ornamental design for a fastener, as shown and described.

DESCRIPTION

FIG. 1 is a perspective view of a fastener showing the new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is an environmental perspective view thereof, shown with an attached call bell device;

FIG. 9 is a front elevation view thereof;

FIG. 10 is a rear elevation view thereof;

FIG. 11 is a top plan view thereof;

FIG. 12 is a bottom plan view thereof;

FIG. 13 is a right side elevation view thereof;

FIG. 14 is a left side elevation view thereof; and,

FIG. 15 is an environmental perspective view thereof, shown attached to a bed rail.

The broken lines adjacent shaded areas represent bounds of the claimed design and illustrate features of the fastener that form no part of the claimed design. All other broken lines illustrate features of the fastener that form no part of the claimed design.

The broken lines showing of the call bell device in FIGS. 8-15 and the bed rail in FIG. 15 illustrates the environment of the claimed design and forms no part thereof. The broken lines in the drawings illustrate portions of the fastener and form no part of the claimed design.

1 Claim, 10 Drawing Sheets
